BINGO BALL DISPENSER

Ben J. Bakos, Arapahoe County, Colo., assignor to King Precision Company, a division of Fire King Company, a corporation of Colorado

Filed Aug. 9, 1965, Ser. No. 86,501

Term of patent 14 years

(Cl. D34—15)

Fig. 1

Fig. 2

FIGURE 4 is a reduced perspective view wherein the base has been made square and the upper chamber has been given four sides to conform to the sides of the base, all as shown.

I claim:

The ornamental design for a bingo ball dispenser as shown and described.
